UNITED STATES PATENT OFFICE

GIUSEPPE RESTUCCI, OF NAPLES, ITALY, ASSIGNOR TO FRANCESCO VITALE, OF NAPLES, ITALY

DEVICE FOR SUPERHEATING AND DRYING STEAM

Application filed June 7, 1923, Serial No. 644,012, and in Italy October 19, 1922.

The present invention relates to a new type of valve for superheating and drying steam for the purpose of realizing fuel economy.

5 Numerous persevering and careful experiments have proved that by causing steam generated for driving motors to flow through conveniently shaped and arranged holes efficient drying of such steam is 10 effected.

The object of the process hereinafter described is to obtain high efficiency in drying and superheating the steam by the subdivision of the steam and to improve the parts 15 composing the valves to render such valves easy to operate.

The said improvements are illustrated in the accompanying drawings in which:

20 Figs. 1—2—3—4 illustrate a valve for use in locomotives,

Fig. 1 being a vertical axial section of such valves,

Fig. 2 being an external view thereof,

Fig. 3 being a plan view thereof,

25 Fig. 4 showing a vertical section of a modified form of the invention.

Figs. 5, 6, 7 illustrate a valve for use in marine boilers,

Fig. 5 being a vertical axial section of 30 such valve,

Fig. 6 being an external view partly in section thereof, and

Fig. 7 being a section on line 7—7 of Fig. 5 while

35 Fig. 8 illustrates both in section and in plan an organ for subdividing steam into very thin thread like streamlets.

The valve illustrated in Figs. 1 to 4 consists of a chamber —a— having an internal flange adapted to be fixed on the steam tube connecting the inside of the dome to the locomotive cylinders. Within said chamber and integral therewith is the seat —b— for 40 piston —c—, which piston is formed with an imperforate skirt c' . Such piston —c— is adapted to reciprocate in the cylinder formed by the upwardly projecting wall —d— in which is located a set of nozzles 45 —f— inclined with respect to the axis of the

valve and arranged in such a way that one nozzle at least will be clear of the lower end of the skirt of the piston when it is in the lowermost position seated upon the seating —b—. The piston is operated by means of 55 a member —h— which is connected to the piston by means of a universal joint —i— and an equalizing valve —l— is provided, one side of which is in communication with the steam space in the dome by means of 60 holes —m— and the other side of which is in communication with the space below the upper wall —n— of the piston, whereby the steam acting on the under side of the piston will act on the piston in conjunction with the 65 steam flowing through the nozzles —f— for raising the piston.

In the modification illustrated in Fig. 4 the operation is substantially the same as in the valve above described, the only difference 70 being a constructional one and consisting in that the piston —c— is placed outside the nozzles —f— which are provided in the wall of the cylinder —d—.

The valve for marine boilers illustrated in 75 Figs. 5, 6, 7 consists of a chamber —a'— provided with an internal hollow cylinder —b'— in the wall of which the nozzles —f'— are provided at a convenient inclination to such cylinder. Within the cylinder 80 —b'— is the piston —c'— which is adapted to be actuated by a screw —h'— and corresponding hand wheel, while holes —m'— are provided to equalize the piston pressure.

The steam coming from the boiler passes 85 through the inlet opening —o— divides into two branches at the pipes —p— and enters the chamber —a'— from which it flows through the nozzles —f— to the outlet —q— to reach the engine in a superheated laminated state. The nozzles —f— (Fig. 8) are 90 preferably conically shaped having at their top a diaphragm provided with holes to augment the steam lamination and drawing.

The inclined position of the nozzles allows 95 a gradual starting of the engine to the boiler of which the valve is applied.

Having now particularly described and ascertained the nature of my said invention 100

and in what manner the same is to be performed I declare that what I claim is:—

1. A device for drying and superheating steam comprising in combination a piston valve comprising a head portion and an imperforate skirt carried directly by said head portion and connected to an external operating organ, a piston cylinder having a plurality of nozzles fixed in the wall thereof such nozzles being adapted to be regulated and opened at will by means of said piston to allow of the passage of steam therethrough, and a valve located in the head of the piston for equalizing the pressure on said piston above and below said head.
2. A device for drying and superheating steam comprising in combination a piston valve comprising a head portion and an imperforate skirt carried directly by said head portion and connected to an external operating organ, a piston cylinder having a plurality of nozzles fixed in the wall thereof, such nozzles being adapted to be regulated and opened at will by means of said piston to allow of the passage of steam therethrough, a seating for said piston and means on the edge of said skirt whereby said piston is adapted to cooperate with said seating to form a positive closure for such device.
3. A device for drying and superheating steam comprising in combination a piston valve comprising a head portion and an imperforate skirt carried directly by said head portion and connected to an external operating organ, a piston cylinder having a plurality of nozzles fixed in the wall thereof such nozzles being adapted to be regulated and opened at will by means of said piston to allow of the passage of steam therethrough, a valve located in the head of the piston for equalizing the pressure on said piston, and means whereby said piston is adapted to cooperate with a seating to form a positive closure for such device.
4. A device for drying and superheating steam comprising in combination a piston valve comprising a head portion and an imperforate skirt carried directly by said head portion and connected to an external operating organ, a piston cylinder having a plurality of nozzles fixed in the wall thereof such nozzles being adapted to be regulated and opened at will by means of said piston to allow of the passage of steam therethrough, a seating for said piston and means whereby said piston is adapted to cooperate with said seating to form a positive closure for such device, such nozzles being arranged in inclined order so that they are opened successively upon the actuation of the piston.
5. A device for drying and superheating steam comprising in combination a piston valve comprising a head portion and an imperforate skirt carried directly by said head portion and connected to an external operat-

ing organ, a piston cylinder having a plurality of nozzles fixed in the wall thereof such nozzles being adapted to be regulated and opened at will by means of said piston to allow of the passage of steam therethrough, a valve located in the head of the piston for equalizing the pressure on said piston, and means whereby said piston is adapted to cooperate with a seating to form a positive closure for such device, such nozzles being arranged in inclined order so that they are opened successively upon the actuation of the piston.

6. A device for drying and superheating steam, comprising in combination, a piston valve comprising a head portion and an imperforate skirt carried directly by said head portion, and an external operating organ for operating the piston, a seating for the base of the piston, an equalizing valve in the head of the piston, a cylinder in which the piston operates, said cylinder being provided with steam superheating and drying elements fixed to the wall of the cylinder, said elements being conically shaped and provided with a diaphragm having holes to subdivide the steam, the position of said elements being arranged spirally in the cylinder wall in order that one at least of them is in communication with an annular chamber formed by the base of the piston and said seating.

In testimony whereof I have hereunto signed my name.

GIUSEPPE RESTUCCI.
